(57) **CLAIM**

The ornamental design for a noodle drinking straw, as shown and described.

DESCRIPTION

FIG. 1 is a perspective view of a first embodiment of a noodle drinking straw showing our new design;

FIG. 2 is a left-side elevational view of FIG. 1, the right-side elevational view being a mirror image thereof;

FIG. 3 is a front elevational view of FIG. 1;

FIG. 4 is a rear elevational view of FIG. 1;

FIG. 5 is an enlarged top plan view of FIG. 1, the bottom plan view being a mirror image thereof;

FIG. 6 is a perspective view of a second embodiment of a noodle drinking straw showing our new design;

FIG. 7 is a left-side elevational view of FIG. 6, the right-side elevational view being a mirror image thereof;

FIG. 8 is a front elevational view of FIG. 6;

FIG. 9 is a rear elevational view of FIG. 6; and,

FIG. 10 is an enlarged top plan view of FIG. 6, the bottom plan view being a mirror image thereof.

The dash dot lines showing a cup and liquid in FIGS. 1 and 6 depict environment and form no part of the claimed design. The evenly dashed broken lines in FIGS. 1-10 represent portions of the noodle drinking straw that form no part of the claimed design.

1 Claim, 6 Drawing Sheets
